U.S. Appl. No. 29/375,831 to Masaki Hashimoto, which was filed on Sep. 28, 2010.

* cited by examiner

Primary Examiner — Garth Rademaker(74) *Attorney, Agent, or Firm* — Greenblum & Bernstein P.L.C.(57) **CLAIM**

The ornamental design for an indoor and outdoor decorative article, as shown and described.

DESCRIPTION

FIG. 1 is a front elevation view of an indoor and outdoor decorative article showing my new design;
FIG. 2 is a rear elevation view thereof;
FIG. 3 is a left side elevation view thereof;
FIG. 4 is a right side elevation view thereof;
FIG. 5 is a top plan view thereof;
FIG. 6 is a bottom plan view thereof;
FIG. 7 is a top, front, left side perspective view thereof;
FIG. 8 is a bottom, rear, right side perspective view thereof;
FIG. 9 is front elevation view thereof, shown at an enlarged scale;
FIG. 10 is rear elevation view thereof, shown at an enlarged scale;
FIG. 11 is a left side elevation view thereof, shown at an enlarged scale;
FIG. 12 is a right side elevation view thereof, shown at an enlarged scale; and,
FIG. 13 is a top, front, left side perspective view thereof, shown in an environment of use.
The broken lines in the figures depict environmental subject matter only and form no part of the claimed design.
